UNITED STATES PATENT OFFICE.

MAXIME MAYER, OF LE VESINET, FRANCE, ASSIGNOR TO JAY THORPE INC., OF NEW YORK, N. Y.

BEADED FABRIC.

Application filed August 24, 1928, Serial No. 301,860, and in France November 30, 1927.

This invention relates to improvements in beaded fabrics used for beaded bags, dresses, umbrella handles, boxes, hats and the like, the object of the invention being to provide 5 an ornamental fabric in which the design is formed by applying the beads in such a way so as to leave gaps in the fabric and expose the ornamental design formed on the backing. 10 A further object is to provide a beaded fabric having ornamental designs executed on the surfaces by leaving gaps between the applied beads the foundation of the gaps being of a contrasting color so as to produce an 15 ornamental and novel effect.

In Figures 2 and 3 is shown the method of sewing the strung beads to the backing which consists of running the thread 4 through a single bead or through two beads, then inserting the thread in the backing and bringing it up again through the cloth and then through the beads again.

For a more general understanding of the invention attention is now called to the drawings in which a preferred embodiment is 25 shown illustrated. In these drawings like parts are designated by like reference characters in all the views.

Figure 1 is a view of the finished beaded 30 fabric showing the executed design.

Figure 2 is a view of the method of sewing the strung beads to the foundation.

Figure 3 is a section on line 3—3 of Figure 2.

Figure 4 is a view of the foundation of the 35 design in the form of stitches or embroidery.

Figure 5 is a view of a modified form of the foundation of the design printed on the 40 backing.

Figure 6 is another modification of the invention showing the design chalk marked on a piece of colored cloth and the cloth sewed to the backing.

Referring now to the drawings in detail 45 number 1 designates the backing of the fabric and 2 a stitch or embroidery formed in the backing. The stitch or embroidery may describe a certain ornamental design and the thread may be colored in order to give a 50 novel effect to the finished product. Around the stitch 2 are sewn a series of threaded beads 3 strung on a thread 4. The space oc-

cupied by the stitches or the embroidery 2 is left open thus forming a gap 5 and exposing same to the surface. 55

In Figures 2 and 3 is shown the method of sewing the strung beads to the backing which consists of applying a cross stitch 6 between each or several of the beads across the thread on which the beads strung thus securely fastening the structure to the backing. 60

In Figure 5 is shown a modification of the device whereby the design 7 is printed directly on the backing in lieu of being stitched and the beads applied in the same manner as 65 shown in Figure 1.

In Figure 6 is disclosed another modification whereby a colored cloth 8 is sewn to the backing and a design 9 chalk marked on the cloth. The beads are then sewn around the 70 chalk mark as in the previous modifications and the chalk then removed exposing the colored backing to the surface. If found expedient the colored cloth may be dispensed with and the design chalked marked directly on the backing. 75

It will thus be seen that I have provided an ornamental and novel method of making beaded fabric having good wearing qualities and which can be manufactured at a relatively small cost. The coloring of the bottom 80 of the gaps may be different than the color of the beads so as to create a contrast. This feature however may be optional. Due to the flexibility of the threaded beads very intricate designs may be easily executed. 85

Having thus described my invention, I claim:—

1. In a beaded fabric of the class described, a backing having a stitch sewed thereon and a 90 series of beads sewed around said stitch, the space occupied by the stitch being exposed, said beads being solidly placed and border on and closely surround the stitch.

2. In a beaded fabric of the class described, a backing having a stitch sewed thereon and a 95 series of beads sewed around said stitch, the space occupied by the stitch being exposed, said beads being solidly placed, and border on and closely surround the stitch.

3. A method of forming designs in beaded fabrics which consists of stitching a design on a backing, sewing a series of beads around 100 said design and leaving the space occupied

by the stitching exposed, said beads being solidly placed, and border on and closely surround the stitch.

4. A method of forming designs in beaded fabrics which consists of embroidering a design on a backing, sewing a series of beads around said design and leaving a gap around the space occupied by the said embroidery.

5. In a beaded fabric of the class described, a backing having a series of embroidery thereon and a series of beads sewed around said embroidery, the space occupied by the said embroidery being free from beads. 10

In testimony whereof I affix my signature.

MAXIME MAYER.
